ABSTRACT: A detachable wiglet to be worn on a woman's hair in any of three positions is disclosed which is constructed by sewing a fringe of hairlike filaments to a foundation of burlap in a spiral pattern beginning near the periphery of the burlap and terminating near the center. The wiglet is an oval shape having a major axis of substantially 7½ inches and a minor axis of substantially 6½ inches.

THREE POSITION WIGLET

This invention relates generally to a detachable coiffure and more specifically to a wiglet.

Wigs have recently become quite fashionable with women in that they allow the wearer to convey the impression of having longer or more hair than she actually has as well as allowing a saving of many hours in the styling and setting of one's natural hair. Partial wigs or wiglets have also met with much favor in that they allow the wearer more flexibility in hair styles as well as augmenting the quantity of one's natural hair.

The prior art coiffures have the disadvantages that they are relatively expensive and that they are generally contoured so as to be worn in only one position.

The present invention overcomes these disadvantages by providing a relatively inexpensive method of constructing a wiglet which wiglet is versatile in that it may be worn in any of three general positions and may be appropriately contoured to fit the chosen position.

The present invention accomplishes this by providing a wiglet which is made by forming natural hair or other hairlike filaments approximately 4 inches in length into a fringe and sewing this fringe to a foundation material such as burlap in a spiral fashion beginning at the outer edge of the burlap and terminating near its center. The thus formed wiglet may be contoured to any desired shape by wetting the wiglet and then allowing it to dry on a head form of the desired shape.

Therefore, it is an object of the present invention to provide a detachable coiffure which may be worn in any of several positions on the head.

It is another object of the present invention to provide an economical method of constructing a wiglet.

It is a further object of this invention to provide a coiffure construction which allows ventilation to the wearer's natural hair and scalp for comfort and health.

A salient object of the present invention is to provide an economical and versatile wiglet.

It is another object of the present invention to provide a wiglet which may be selectively contoured and worn in any of three general positions.

These and other features and advantages will become readily apparent from the following detailed description of a specific embodiment of the invention wherein:

FIG. 1 is a top plane view of the wiglet being worn in the top front position;

FIG. 2 is a top plane view of the wiglet being worn in the crown position;

FIG. 3 is a top plane view of the wiglet being worn in the nape position;

FIG. 4 is a cutaway perspective view showing the construction of the top of the wiglet; and

FIG. 5 is a cutaway perspective view of the bottom of the wiglet showing the details of the construction.

Referring now to FIG. 1, the detachable coiffure is shown in position on a wearer's head so that the front of the wiglet 1 coincides with the wearer's natural hairline. This is referred to as the top front position.

Similarly, FIG. 2 shows the detachable coiffure worn in the crown position, and FIG. 3 shows it in the nape position. When worn in this last position, the coiffure's top will be even with the top of the ears, and it will serve as a fillin for the entire nape section.

Turning now to FIG. 4, the wiglet is seen to be constructed

on a foundation of flexible sheet material 2 such as burlap. A fringe 3 of human hair 4 4 inches in length is sewn to the burlap foundation in a spiral pattern beginning on the periphery at 5 and terminating near the center of the wiglet. The point of termination 6 is shown in FIG. 5.

FIG. 5 shows a cut away view of the bottom of the wiglet with the stitching 7 progressing in a spiral fashion from the periphery toward the center terminus in the direction indicated by the arrowheads. The foundation material 2 is then covered by a second sheet of flexible material 8 such as burlap which is similar to the foundation material 2. This second sheet serves to cover the stitches 7. A nylon net 10 may then be affixed over the second sheet for appearance purposes. The several layers are now sewn together and finished with a cotton bias tape 9.

The finished wiglet is now seen to consist of a net 10 upon which is a layer or sheet of burlap 8 which in turn is below the foundation sheet of burlap 2. To the top side of this foundation layer, the fringe 3 of hair approximately 4 inches long is sewn in a continuous spiral. The wiglet is finished around its periphery with the tape 9.

It is important that the fringe be sewn to the foundation beginning on the periphery and terminating near the center of the wiglet to prevent the process from causing the oval shaped foundation to cup or distort.

The novel utility of the invention should now be apparent. Using burlap as the foundation material allows the user to wet the wiglet and then place it on a head form to dry. When dried, the wiglet will retain the contour given it by this process. A user may thus contour the wiglet to achieve the proper fit for wearing in any of the three general positions shown in FIGS. 1, 2, and 3. Further, the wiglet while initially being formed of straight hair as shown in FIG. 4 may be set to any hair style desired.

It is desirable that the wiglet have a major axis of between 7 and 8 inches and a minor axis of between $5\frac{1}{4}$ and $6\frac{1}{4}$ inches. These dimensions have been found desirable because they allow the wiglet to be worn in each of the three positions by most users. In one preferred embodiment $6\frac{1}{4}$ by $7\frac{1}{4}$ inches has been found to be suitable.

While the instant invention has been shown and described herein in what is conceived to be the most practical and preferred embodiment, it is recognized that departures may be made therefrom within the scope of the invention, which is therefore not to be limited to the details disclosed herein but is to be accorded the full scope of the appended claims.

I claim:

1. A detachable coiffure to be worn on and at least augment a woman's hair comprising: a foundation of flexible sheet material, a fringe of hairlike filaments sewn to a first side of said foundation in a spiral pattern beginning at the outer edge and terminating near the center, and a second sheet of flexible material affixed to a second side of said foundation.

2. A coiffure as set forth in claim 1 wherein said foundation is oval in outline having a major axis of $7\frac{1}{2}$ inches and a minor axis of $6\frac{1}{4}$ inches.

3. A coiffure as set forth in claim 1 in which said second sheet has an inner fabric lining and wherein the edges of said foundation, second sheet, and lining are bound circumferentially with tape.

4. A coiffure as set forth in claim 3 wherein said foundation and said second sheet are made of burlap.
